UNITED STATES PATENT OFFICE

143,428

DESIGN FOR AN OCCASIONAL TABLE

Max S. Karp, Los Angeles, Calif.

Application August 29, 1945, Serial No. 121,718

Term of patent 14 years

(Cl. D33—14)

To all whom it may concern:

Be it known that I, Max S. Karp, a citizen of the United States, residing at 6106 Tenth Avenue, Los Angeles, in the county of Los Angeles and State of California, have invented a new, original, and ornamental Design for an Occasional Table, of which the following is a specification, reference being had to the accompanying drawing, forming part thereof.

Fig. 1 is a perspective view of an occasional table, showing my new design.

Figs. 2 and 3 are end views thereof as seen, respectively, from the left and right of Fig. 1.

I claim:

The ornamental design for an occasional table, substantially as shown.

MAX S. KARP.
